(57) **CLAIM**

The ornamental design for a trap panel, as shown and described.

DESCRIPTION

FIG. 1 is a perspective view of a trap panel of the present invention;

FIG. 2 is a front elevational view of the trap panel of FIG. 1;

FIG. 3 is a front elevational view of an enlarged portion of the trap panel of FIG. 2;

FIG. 4 is a rear elevational view of the trap panel of FIG. 1;

FIG. 5 is a bottom plan view of the trap panel of FIG. 1, the top view being a mirror image thereof; and,

FIG. 6 is a right side elevational view of the trap panel of FIG. 1, the left side view being a mirror image thereof.
